UNITED STATES PATENT OFFICE.

DAVID P. DAVIES, OF RACINE, WISCONSIN, ASSIGNOR TO J. I. CASE THRESHING MACHINE COMPANY, OF RACINE, WISCONSIN, A CORPORATION.

SAFETY STARTING DEVICE.

1,162,225.

Specification of Letters Patent. Patented Nov. 30, 1915.

Application filed April 19, 1915. Serial No. 22,326.

To all whom it may concern:

Be it known that I, DAVID P. DAVIES, a citizen of the United States, residing at Racine, in the county of Racine and State 5 of Wisconsin, have invented certain new and useful Improvements in Safety Starting Devices, of which the following is a specification.

In operating high power gas tractors the 10 engine is commonly started by manually turning the fly-wheel or by means of a crank connected with the engine. When employing a crank it is generally so arranged that when the engine starts the crank is automatically released, but should the engine 15 reverse its motion such crank does not become released but reverses suddenly and forcibly by the action of the engine, in many instances resulting in serious injury 20 to the operators.

The object of my invention is to provide a safety starting device for gas engines which will eliminate the possibility of injury to an operator under the conditions stated, and 25 which can be conveniently and readily manipulated.

In the accompanying drawings, which form a part hereof, Figure 1 is a side elevation of a gas tractor showing my invention 30 as applied thereto; Fig. 2, a front elevation of the starter and devices coöperating therewith; Fig. 3, a side elevation of the same, and Fig. 4 is a vertical section thereof.

In said drawings the portions marked 5 35 indicate an engine of any appropriate construction, upon the crank-shaft, 6, of which I fixedly mount a ratchet-wheel 7. At one side of said ratchet wheel and loosely mounted on shaft 6 is a yoke, 8, which is free to 40 turn on said shaft 6 and which terminates in a shank, 9. In said shank 9 I provide a dog, 10, which is normally held therein by a spring, 11, said dog being provided with a pin, 12, for a purpose which will hereinafter 45 appear. Upon the engine 5 I provide a trip, 13, and a latch, 15, each of which co-operate with the starter in a manner to be stated.

In operating my improved starter I preferably employ a removable handle comprising a suitable bar or pipe 16, which is inserted in the shank 9 with sufficient force to project dog 10 into engagement with ratchet-wheel 7. Yoke 8 by means of said 55 handle is turned upwardly the distance de-

sired, and then, as dog 10 engages the ratchet at such point, the movement of the yoke is slowly reversed, said yoke at the same time turning said ratchet-wheel and crank-shaft 6 in the same direction until the 60 engine is near the end of its compression stroke, when a quick downward pull is given to throw the same past compression, or, in other words, to crank the engine past center and into regular action, upon which occurrence handle 16 is withdrawn. However, when performing this operation, should the engine reverse or "kick back" when yoke 8 is pulled downwardly, and the dog 10 be still engaged, said yoke will also be carried 65 in the same direction by the ratchet until pin 12 contacts with trip 13, which pin, when it strikes the stop, 14, of said trip, will throw dog 10 out of engagement with said ratchet-wheel, so that the yoke will 70 cease revolving and be under complete control of the operator, leaving the engine free to spin in the reverse direction from that of starting. After the engine has been started, or when it is not in operation, handle 16 is 75 withdrawn, and said yoke, with the parts associated therewith, may be fixedly held from movement by turning it to the position indicated by dotted lines in Fig. 2, when pin, 17, in shank 9 will become engaged with latch 15, thus securing the starter in fixed 80 position until desired for further use, as will be readily understood.

I have illustrated my improved starter in 85 connection with a large traction engine, as it is particularly adapted for use with the same by reason of the height at which the engine is located, which otherwise would be inconvenient for cranking in the ordinary way, but I desire to be understood that it 90 may be applied to engines for other purposes.

I claim as my invention:

1. A starter for engines, comprising a 100 ratchet-wheel, a yoke associated therewith, a dog associated with said yoke and adapted to engage said ratchet-wheel, removable means adapted to be inserted in said yoke to contact with said dog and engage the same with said ratchet, and means for automatically disengaging said dog therefrom.

2. A starter for engines, comprising a 105 ratchet-wheel, a revolute yoke associated therewith, a shank associated with said yoke, a spring-controlled dog in said shank, re-

movable means adapted to be inserted in said shank to engage said dog with said ratchet-wheel, and means for disengaging said dog therefrom.

- 5 3. In a starter for engines, a revoluble member adapted to be mounted upon an engine-shaft, a ratchet wheel associated therewith, means associated with said member for engaging said ratchet whereby said member and ratchet may be revolved to-

Copies of this patent may be obtained for five cents each, by addressing the "Commissioner of Patents, Washington, D. C."

gether, means associated with said member for disengaging it from said ratchet, and means for fixedly securing said member in position when so disengaged.

In testimony whereof I affix my signature 15 in presence of two witnesses.

DAVID P. DAVIES.
